Fig. 1.

UNITED STATES PATENT OFFICE.

ALEXANDER THOMSON, OF SOUR LAKE, TEXAS.

BACK-PRESSURE VALVE.

Application filed March 6, 1926. Serial No. 92,947.

My invention relates to back pressure valves for use in oil well operations.

When an oil well has been drilled to a sand which is considered productive and a test thereof is desired, it is common to insert a well screen or perforated pipe having thereon a back pressure valve, and then wash out the well and test the supposed producing stratum. If the test is not satisfactory and it is desired to drill deeper, it frequently happens that the screen can not be removed as it becomes lodged or "frozen" in place. With the ordinary back pressure valve, it then becomes necessary to insert a milling cutter or drill and cut up the valve and remove it in pieces. This is a difficult and expensive operation but there is no alternative except the shooting or blasting of the screen and valve so as to open up a passage for the drill through the stratum which has been tested.

It is an object of my invention to construct a back pressure valve and a set collar to accompany the same which may be attached to the lower end of the screen and permit the removal of the back pressure valve when it is desired. It is also an object to construct the back pressure valve so that the valve may be positively opened during the operation of washing the well in order to test the formation in which the screen is set. It is a further object to construct the valve and its housing so that the sand and sediment may be washed clear from the valve when it is desired to remove it from the well. Invention resides particularly in the construction and arrangement of the parts thereof, which will be illustrated in detail hereafter.

Referring to the drawing herewith, wherein a preferred embodiment of the invention is disclosed, Fig. 1 is a central longitudinal section through my improved back pressure valve illustrating its connection to the lower end of the strainer. Fig. 2 is a side elevation of the upper section of my valve. Fig. 3 is a transverse section on the plane 3-3 of Fig. 1. Like numerals of reference are employed to designate like parts in all the views.

In the drawing I have shown a perforated pipe or screen as being connected by a collar 2 to a set collar 3 of my valve. Said

set collar is connected at its lower end by means of the coupling 4 to the pipe or shoe 5 extending to the bottom of the well.

The set shoe 3 is preferably threaded on its upper end, as shown at 6, with a left-hand thread so that its rotation in a right-hand direction will only serve to tighten the collar within the coupling 2. The set collar is a tubular structure having the walls recessed slightly between the ends, as shown at 8, thereby producing an inwardly projecting threaded portion 9 at the upper end 65 and a smooth inner side 10 at the lower end.

The threaded portion 9 at the upper end of the set collar is connected by means of a left-hand thread to the head 11 constituting the upper member of the valve chamber. 70 This member has a central tubular passage 12 therethrough, the upper end of which is enlarged and threaded interiorly at 13 to provide attachment for a setting tool. The lower end of the enlarged portion is beveled at 14 to provide a seat for the nipple 15 of the wash pipe. The chamber within the upper threaded portion 13 is provided with radial openings 16 connecting with the space 17 outside the head of the valve and 80 between the same and the lower wall of the screen 1. The lower end of the head 11 is reduced in outer diameter and threaded to receive the upper end 18' of the valve chamber. The general outer appearance of the 85 head portion 11 is shown in Fig. 2.

The valve chamber, included within the housing 18, is adapted to receive two separate valves. For this purpose, the lower end of the passage 12 through the head of 90 the valve chamber is beveled at 19 to form a lower seat for a valve member 20. The lower end of the chamber 18 is extended inwardly and an upwardly tapered opening 21 is formed therein to receive a second 95 valve member 22.

The upper valve 20 is a hollow member closed at its outer end and tapered at 23 to fit within the seat 19. It is held resiliently in position closing the passage 12 by means 100 of a spring 24 bearing against the lower flanged portion 25 of the valve. The said spring 24 bears at its lower end against a perforated disc 26 fitted within the lower end of the valve chamber. The valve member 20 includes an inner chamber 27 open

at its lower end provided with a plurality of lateral openings 28 connected with the interior of the valve chamber 18.

The lower valve 22 has a tapered disc fitting within the seat 21 and has an upwardly extending guide rod 29. Said rod extends through a central opening in the disc 26 and has a nut and washer 30 at the upper end thereof which furnishes a bearing for a compression spring 31, which bears against the disc 26 at its lower end and tends to hold the valve 22 resiliently upwardly within its seat.

In the use of this device the strainer 1 with the back pressure valve described will be inserted into the well and set at the desired position therein. The well will then be washed and in doing so a wash pipe 32 will be inserted downwardly into the screen. 15 This wash pipe is formed with the nipple 15 at its lower end reduced to fit within the passage 12 and forming a nozzle therefor. The lower end of the nozzle is formed with curved notches 33 therein to allow the passage of fluid more freely around its lower opening. It is contemplated that when the wash pipe is placed in position a tapered shoulder 34 thereon will contact with the seat 14 and close the passage of water upwardly. 20 The end of the wash pipe will contact with the valve member 20 and depress it so that water may wash around the upper valve freely and downwardly through and past the valve 22 and through the pipe 5 into the 25 lower end of the well, coming up outside the pipe and strainer to the surface. When the well is thus washed, the wash pipe will be withdrawn and the well may then be tested.

If it should happen that the back pressure valves, which I employ, do not appear to function properly, and it becomes necessary to withdraw them, or if the test proves unsuccessful and it is desired to remove the back pressure valves, a setting tool will be 40 inserted downwardly into the well, the lower end being threaded to engage the threaded portion 13 of the head member of the valve chamber. When the threaded tool has been 45 screwed within the seat 14, the continued 50 rotation of the setting tool will rotate the head 11, as previously stated. The connection of the head at 9 is a left-hand threaded connection, therefore, the rotation of the head 11 in a right-hand direction will unscrew the valve from the setting collar and it will be freed therefrom and may be withdrawn with the setting tool from the well. 55 The lower end of the chamber has a sliding fit only at 10 and may be easily withdrawn. 60 Should there be sand or sediment lodged about the upper end of the head 11, tending to lock it in position, water may be pumped down through the setting tool and as the lower end of the pipe 5 is usually closed 65 and the passage of fluid upwardly outside

the pipe cut off, the fluid will pass through the openings 16 into the lower end of the screen and will wash upwardly therein carrying with it the sand lodged in the chamber or recess 17. When the sand is thus cleared 70 from around the valve chamber, the valve may be readily removed.

If the valve needs adjustment, the adjustment may be made and the valve again inserted. If, however, it is desired to drill 75 deeper, a reamer may be inserted to cut away the set collar 3 or such portion thereof as is necessary to admit the passage of the drill bit, and the hole may then be deepened. It will be obvious that the removal of the valve 80 chamber and the valves therein from the lower end of the screen will leave very little metal to be cut by the drill in order to allow its passage through the screen into the stratum below for the purpose of deepening 85 the hole. The advantages of this construction will be apparent without further description.

What I claim as new and desire to protect by Letters Patent is:

1. In a device of the character described, a set collar adapted to be secured to the lower end of a pipe or screen, a valve casing head having a left-hand threaded engagement in the upper end of said collar, said head having an interiorally right-hand threaded seat at its upper end and a passage below said seat, a valve chamber below said head and secured thereto, and a plurality of upwardly opening valves in said chamber.

2. In a device of the character described, a tubular set collar adapted to be secured to a pipe or screen, a valve casing head having a left-hand threaded engagement within the upper end of said collar, the upper end of said head projecting above said collar and having a right-hand thread thereon for engagement with a setting tool, a valve casing secured to the lower end of said head and fitting slidably within the said collar, and a downwardly opening valve in said casing.

3. In a device of the character described, a tubular set collar adapted to be secured to a pipe or screen, a valve casing head having a left-hand threaded engagement within said collar, the upper end of said head extending above said collar and having an interior right-hand-threaded seat therein, said seat having lateral openings therein, a valve casing below said head fitting slidably in said collar and downwardly opening valves in said casing.

4. In a device of the character described, a back pressure valve adapted to be attached at the lower end of a pipe or screen, said valve comprising a tubular head threaded on its outer face with a left-hand thread, a valve chamber below said head, and a downwardly opening valve in said chamber.

5. A back pressure valve adapted to be

- connected by a left-hand threaded engagement at the lower end of a pipe or screen, said valve comprising a tubular head having a passage therethrough the upper end of which is enlarged and threaded in a right-hand direction, a tapered shoulder at the lower end of said threaded end, a valve casing below said head, and a downwardly opening valve therein.
10. A back pressure valve adapted to be connected to a screen or pipe, said valve comprising a tubular head, the outer face of which is threaded in one direction for attachment to a supporting member, an interior seat at the upper end threaded in the opposite direction, a valve casing below said head and removable therewith, and downwardly opening valves in said casing.
15. 7. A back pressure valve comprising an upper head member adapted for detachable engagement with a supporting pipe or screen,
20. 8. A valve casing secured at the lower end of said head, a valve seat at the lower end of said head, a valve held resiliently therein, said valve comprising a hollow member closed at its upper end and open at its lower end, and having lateral openings therein for the purpose described.
25. 9. A back pressure valve comprising an upper head member formed for detachable connection with a pipe or screen, said head having a central passage with valve seats at the upper and lower ends thereof, a valve casing at the lower end of said head member, a valve closing the lower end of said passage and a second valve closing the lower end of said casing.
30. 10. In testimony whereof I hereunto affix my signature this 27th day of February, A. D. 1926.

ALEXANDER THOMSON.
